[57] CLAIM

The ornamental design for a combined clock, writing
instrument and holder therefor, as shown and described.

DESCRIPTION

FIG. 1 is a perspective view of the front and top of a
first embodiment of a combined clock, writing instru-
ment and holder therefor showing my new design;
FIG. 2 is a top plan view thereof, the bottom being plain
and unornamented;
FIG. 3 is a rear elevational view thereof;
FIG. 4 is right side elevational view thereof;
FIG. 5 is a left side elevational view thereof;
FIG. 6 is a perspective view similar to FIG. 1 of a
second embodiment of a combined clock, writing in-
strument and holder therefor;
FIG. 7 is a top plan view thereof, the bottom being plain
and unornamented;
FIG. 8 is a rear elevational view thereof;
FIG. 9 is a right side elevational view thereof; and,
FIG. 10 is a left side elevational view thereof.
